UNITED STATES PATENT OFFICE.

ROBERT A. PONSELLE, OF NEW YORK, N. Y.

ROTARY FLOOR-MACHINE.

1,228,476.

Specification of Letters Patent.

Patented June 5, 1917.

Application filed August 26, 1914. Serial No. 858,730.

To all whom it may concern:

Be it known that I, ROBERT A. PONSELLE, a citizen of France, and resident of the borough of Manhattan, in the city and State of 5 New York, have invented a new and useful Improvement in Rotary Floor-Machines, of which the following is a specification.

My invention relates to a device adapted to be used in connection with a rotary floor 10 machine and controlled and operated thereby, with the object in view of providing a device that will scrape, plane or surface a floor quickly and economically.

A further object is to provide a device 15 that will carry one or more knives or scrapers which may be independently adjusted as well as independently removed from the device.

With these objects in view, my invention 20 consists in certain features of construction, form and arrangement of the several parts as will be hereinafter more fully described and pointed out in the claims.

A practical embodiment of my invention 25 is represented in the accompanying drawings, in which—

Figure 1 represents a side elevation of my device attached to a motor for rotating it,

Fig. 2 represents an inverted plan of the 30 same,

Fig. 3 represents in detail a transverse central section taken in the plane of the line A—A of Fig. 1, and

Fig. 4 represents a horizontal section taken 35 in the plane of the line B—B of Fig. 1.

The device comprises a frame having an upper plate 1 and a lower plate 2, which plates are spaced apart by means of bosses 3 cast on the plate 1.

40 The lower plate 2 is secured to the upper plate 1 by means of screws 4 countersunk in the plate 1 and threaded into the bosses. This plate 2 is cut away at 5 for the reception of holders 6 adapted to receive knives or scrapers 7, adjustably held therein. In the present instance, I have shown three, but it will be understood that I may use one or more holders and scrapers.

The side walls of the cutaway portions 5 50 are parallel and provided with grooves 8 adapted to receive tongues 9 of the holders 6. The holders are held in position in the plate 2 by means of a spring 10, one end of which is secured to the plate 2 and the other end having a hole 11 arranged to engage a pin 12 on the holder.

The scraper 7 is adjustably held in the throat 6* of the holder by means of a swinging clamp 13 pivoted at 14 upon opposite sides of the throat. 60

The clamp 13 is provided with a swinging member 15 pivoted at 16, which member secures the knife or scraper vertically in position by means of a thumb screw 17 threaded in the member with the end of the 65 screw engaging the scraper, thereby forcing the member to rock on its pivot 16 and pinch the scraper between the clamp 13 and members 15 at a point below the pivot 16.

The radial adjustment of the clamp 13 is 70 accomplished by means of an adjusting screw 18 pivoted to the clamp at 19, the free end of which screw passes through a lug 20 on the holder and has thumb nuts 21, 22, located upon opposite sides of the lug 20, 75 for locking the screw and clamp in position. The holder is also provided with a sole 23 of hard wood, fiber, or other suitable material, which is secured by bolts 24 countersunk therein and nuts 25. The sole 23 also 80 has a throat 26 which registers with the throat 6* of the holder.

The cutting edges of the several scrapers 7, as shown in Figs. 2 and 4, are arranged 85 at different angles to each other, for instance, the edge of one scraper is shown radial with respect to the circular path of motion, while the other two scraper edges are shown oblique to the path of motion, but I wish it understood that I may arrange all 90 the cutting edges radial or all oblique to the path of motion.

The upper plate 1 is provided with a clutch member 27 which is adapted to engage a clutch member 28 secured to a driving disk 29. This disk 29 is horizontally mounted on a hollow shaft 30 journaled in a gear casing 31 fixed to the motor 32. Rotary motion is imparted to the disk 29 from the drive shaft 33 of the motor through a 95 train of gears 34, 35, 36, 37, of which the gear 37 is mounted upon the hollow shaft 30. 100

A handle 38 is fixed to the gear casing 30 with which the operator pushes the machine over the floor to be scraped or planed. 105

In operation, the scrapers are adjusted in their holders and the holders locked in the lower plate 2. The upper plate carrying the lower plate with its holders and scrapers 110 is then placed in position to be clutched by the driving clutch member 28 on the disk 29 engaging the member 27. The motor

may now be started and motion will be transmitted through the train of gears to the disk and thence to the upper and lower plates, when the scrapers will be caused to travel in a circular path, while the operator passes the machine over the floor from place to place.

It has been found, that, at the high speed at which the scrapers are driven, a vast amount of floor may be surfaced or finished in a very short time, thereby saving considerable time, labor and expense.

It is evident that slight changes might be resorted to in the form, construction and arrangement of the several parts without departing from the spirit and scope of my invention; hence I do not wish to limit myself strictly to the structure herein set forth, but

What I claim is:—

1. A device of the character described comprising a frame provided with upper and lower plates, holders having a tongue and groove connection with the lower plate, means for locking the holders in the lower plate, scrapers mounted in said holders, a clutch member on the upper plate, and means engaging the said clutch member for rotating the frame.

2. A device of the character described com-

prising a frame provided with upper and lower plates, holders having a tongue and groove connection with the lower plate, spring actuated means for locking the holders in the lower plate, scrapers mounted in said holders, a clutch member on the upper plate, and means engaging the said clutch member for rotating the frame.

3. A device of the character described comprising a frame provided with upper and lower plates, holders having a tongue and groove connection with the lower plate, means for locking the holders in the lower plate, said means comprising a pin on the holder and a spring secured to said lower plate and having a hole for the reception of said pin, scrapers mounted in said holders, a clutch member on the upper plate, and means engaging the said clutch member for rotating the frame.

In testimony, that I claim the foregoing as my invention, I have signed my name in presence of two witnesses, this seventeenth day of August, 1914.

ROBERT A. PONSELLE.
